PORTABLE AUTOGRAPHIC REGISTER

Filed April 22, 1925

UNITED STATES PATENT OFFICE

EDWARD KIRBY BOTTLE, OF ELMIRA, NEW YORK, ASSIGNOR TO AMERICAN SALES BOOK COMPANY, LIMITED, OF TORONTO, CANADA, A CORPORATION OF ONTARIO

PORTABLE AUTOGRAPHIC REGISTER

Application filed April 22, 1925. Serial No. 24,937.

This invention relates to improvements in autographic registers or the like, and more particularly in some of its details, to such registers portable in nature or capable of being carried in the hand when in use.

It is a general object of the invention to provide a register of the class mentioned which is simple and inexpensive in construction, convenient and efficient in use, and strong, yet so light as to render it readily portable and capable if necessary of being carried in the hand while in use without undue strain or fatigue upon the user.

Another object is to provide an autographic register having an improved construction for housing the supply record strip and the transfer or carbon strip, and to provide a protection for these supply strips from injury or exposure to dirt, moisture and the like.

Still another object is to provide an autographic register having an improved and convenient arrangement for regulating the feed of the record strip or strips so as correctly to position them for entry of a record thereon.

Another object is to provide an improved clamping means for the forwardly fed parts of the record strips, which may be also utilized as a tear-off edge for the forwardly fed used parts of the strips.

Another object is to provide an improved supporting device for registers of the class mentioned so as to steady and support the register in the hand of the user.

Other objects will be in part pointed out in connection with the following detailed description and will be in part obvious in connection therewith.

The invention accordingly comprises the features of construction, combinations of elements, and arrangement of parts, which will be exemplified in the construction hereinafter set forth and the scope of the application of which will be indicated in the claims.

For a more complete understanding of the nature and objects of the invention reference is had to the following detailed description and to the accompanying drawings disclos-

ing illustrative but preferred embodiments of the invention, and in which

Figure 1 is a vertical longitudinal section taken approximately on the line 1—1 of Fig. 2 looking in the direction of the arrows and showing an autographic register embodying the invention; 55

Fig. 2 is a plan view of the same, parts being broken away and shown in horizontal section; 60

Fig. 3 is a vertical transverse section taken approximately on the line 3—3 of Fig. 2 looking in the direction of the arrows; 65

Fig. 4 is an enlarged fragmentary vertical section showing the strip positioning and aligning device; 65

Fig. 5 is a view similar to Fig. 4, the strips being shown in a different position;

Fig. 6 is a plan view of a portion of a record strip for use in the register; 70

Fig. 7 is a partial plan view similar to Fig. 2 but showing a modification; and

Fig. 8 is a fragmentary vertical section taken approximately on the line 8—8 of Fig. 7. 75

Referring to the drawings for a detailed description of the embodiments of the invention thereshown, there is represented an autographic register having a casing constructed of some light strong material, as sheet metal, the bottom, side and top walls being formed in one integral piece bent and shaped to form the complete register casing. The integral piece of material forming the casing may be cut from a sheet metal plate and then bent and shaped to form the casing. The end wall 10 of the casing may also be integral with the bottom plate as shown in Fig. 1. The opposite or forward end of the casing is provided with a passageway communicating with the interior compartment and a closure or door 11 is provided for this passageway being hinged at its lower edge as at 12 and pressed towards closed position by a spring 13. The interior compartment thus provided may be employed as a storage compartment or housing for a supply of record strips, for example the zigzag supply pad 14 which may be made up of one folded record strip, but preferably includes a plu- 80

85

90

95

100

rality of interfolded superposed strips 15. This supply pad or pack is substantially equal in horizontal dimensions to the horizontal dimensions of the compartment and 6 may be inserted into the compartment through the opening at the end of the casing, the door 11 being swingable outwardly for this purpose. A flange 16 is bent upwardly from the forward end of the bottom 16 plate forming a retaining ledge for the supply pack and also forming a stop to limit the inward swinging movement of the door 11.

The upper wall of the casing overlies the 15 storage compartment forming a platen or writing table 17 over which the record strips pass, being supported thereby for entry of a record on the strips as by writing. At the forward part the writing table is bent 20 downwardly to form a flange 18, preferably inwardly inclined and forming a transversely disposed acute angled apex or edge 19 around which the record strips turn in passing from the storage compartment to the 25 writing table, the edge 19 being such as to cause the strip or strips to bend quite sharply when pressed thereagainst.

The door 11 terminates short of the writing table 17, its upper edge lying near the 30 flange 18 and being positioned inwardly slightly from said flange and spaced therebelow providing a slot or passageway 20 through which the record strips emerge. At the opposite side of the apex 19 from the 35 edge of the door 11 is a guiding and retaining member 21 spaced slightly above the writing table under which the strips are threaded. The edge of the door 11 and the plate 21 thus form guides at opposite sides 40 of the apex 19 restraining the strips in passage to said apex and compelling them to turn thereabout through a considerable angle.

As shown in Fig. 6, the strips 15 are preferably provided with a series of blank forms 45 22 spaced therealong, the adjacent blank forms being separated by transverse lines 23 formed by structural modification of the strip so as to decrease its resistance to folding or bending and insure accurate tearing along such lines. A convenient method of forming these modified lines is by weakening the strips as by a series of small perforations. Each sheet or leaf between adjacent 50 folds 23 may be provided with apertures 24 which may be utilized for convenient filing of sheets when severed from the strips, or they may be utilized for effecting alignment of the strips relatively to each other as appears more fully below.

It will be understood that the resistance to bending of the strips 15 transversely of their length is greater along the body thereof than at the weakened lines 23, the result 55 being that the strips arch across the edge

19 as indicated diagrammatically at 25 (Fig. 4) when the strips are being fed forwardly, the upper edge of the door 11 and the transverse plate 21 then acting as guides to position the strips into this arch position. Due to this arching, there is very little resistance to feeding of the strips by the edge 19 which is preferably quite acute, though rounded so as to avoid penetration or scratching of the surface of the contacting 75 strip. When however the transverse weakened lines 23 approach the edge 19, the strips bend sharply around the edge as represented diagrammatically in Fig. 5, the edge then entering the sharp bend or angle in the strips and functioning as a detent to increase the resistance to feeding of the strips. There is therefore a tendency to check the feeding of the strips which is readily overcome however by increasing the feeding 80 stress upon the strips to spring them away from the sides of the transverse edge to assume again the arched position indicated in Fig. 4. The edge or detent 19 is so positioned with reference to the writing table that the strips and the blank forms thereon are in correct writing position over the writing table when checking of the strip feed, as described, occurs.

In addition to the checking action mentioned, the sudden increase in feeding resistance causes a sudden jerk upon the feeding hand of the operator, thus signaling or notifying him that the strips are in correct position. Proper feeding and positioning of 100 the strips can thus be accomplished without visual observation or exercise of special care as it is quite obvious to the operator that the strips are in proper position when the signaling jerk occurs and the temporary 105 checking action takes place.

The strips are also always maintained in substantial alignment longitudinally to keep the blank forms on the superposed sheets in correct writing registry, this function being 110 promoted by means of the transverse edge or apex 19. The transverse weakened lines of the superposed strips ordinarily approach the apex in substantial alignment with each other, but in case one of the strips chances 115 for some reason to be lagging slightly behind the others, the checking action of the advance strip or strips occurs slightly before that of the lagging strip, offering an opportunity for the latter to creep upon the 120 the others, and to assume its correct registering position. In this manner substantial alignment of the strips and of the blank forms thereon is maintained. In case one of the strips, as through accident, happens to 125 lag even considerably behind the others, it will, through operation of the transverse apex, creep up on the others into correct 130 registry in the interval of a very few feeding periods. This alignment is further pro-

moted by reason of the fact that there is a tendency due to the resiliency of the paper, for the parts of the strips following the transverse lines 23 when assuming substantially the position shown in Fig. 5, to spring horizontally away from the apex, thus re-tracting slightly over the writing table any strip that may be slightly in advance of the others. Any substantial longitudinal dis-alignment of the strips, such as may have taken place when the strips are threaded into the machine or through accident or otherwise, may be readily corrected by pulling the strips individually, beginning with the lowermost, until each is in turn checked by the transverse apex 19.

A clamping plate 26 for the forwardly fed ends of the record strips is pivoted to the casing through depending flanges 27 so as to be capable of swinging upwardly as shown in dot and dash lines in Fig. 1, being biased to clamping position by means of a spring 28. An outturned flange 29 is preferably provided on one of the depending flanges 27 to form a lug for manually raising and lowering the clamping plate. The forward edge of the clamping plate provides a tearing edge across which the forwardly fed record strips may be severed, being for this purpose spaced to register approximately with the transverse lines 23 when the strips are checked by the transverse edge 29 as described. The rear end of the writing table may be notched as at 30, underlying the tearing edge of the clamping plate 26 so as to facilitate grasping of the strip ends after severance of the extending ends. The end wall 10 may also be notched as indicated at 31 for this purpose.

40 A supporting or retaining strap or bail 32 may be attached to the lower rear end of the casing so as to extend over a supporting hand of the operator to steady the register in supported position. A cushion or bearing plate 33 may be attached to the hand bail 32 for contact with the operator's hand.

A tubular housing 34 for a supply roll of transfer strips is provided at one side of the writing table, having a rotary sliding cover 35 for covering the receiving opening in the side of the housing, this cover being shown in Fig. 3 as assuming position to uncover the opening. The transfer strips extend from the housing 34 through the opening therein over the writing table and between adjacent record strips, the free ends thereof being clamped to the opposite side of the register by means of a clamping bar 36 pivoted at one end and retained at its opposite end in clamping position by means of a keeper 37.

The modification shown in Figs. 7 and 8 is similar to that above described and similar parts are designated by similar reference numerals with addition of the index *a*. In

this modification however stub aligning posts 38 are provided spaced to correspond to the spacing of the apertures 24 in the record strips and having conical surfaces as shown, so as to enter said apertures and thereby effect longitudinal alignment of the strips with reference to each other and also to correctly position the strips laterally and longitudinally and to align them over the writing table. These aligning posts are positioned adjacent the rear edge of the clamping plate 26*a* which is notched as at 39 to receive the posts. Depression of the clamping plate into clamping position will therefore force the record strips into position over the aligning posts.

The aligning pins or posts 38 as mentioned lie adjacent to the clamping bar 26*a* and are thus spaced at a definite distance in advance of the strip checking edge or detent 19 so that the pins enter the strip apertures when the folds or creases of the record strips come into alignment with said detent. Therefore, when the clamping bar is moved downwardly into clamping position, the apertures of the record strips are caused to engage over the pins when the strips are forced downwardly. This not only aligns the strips by virtue of the conical formation of the pins as mentioned but the strips are simultaneously engaged at parts spaced longitudinally near opposite ends of the platen or writing table, so as to cause the strips to lie flat and smooth in writing position avoiding wrinkles, folds and other irregularities. These posts also serve to assist in retaining the strips against the clamping bar 26*a*, when pressure of said bar is relieved.

As above suggested the casing of the register may be made so light and small as to be readily portable, or capable of being carried in one hand while the other makes the entry upon a record strip, but it will be understood that important features of the invention, such for example as the feature relating to positioning the record strips for entry of a record, and signaling to the operator when the strips are thus positioned, are applicable to other types of registers, and their use in such connection is contemplated.

Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a device of the character described,

in combination, a casing having a compartment for storing a record strip, a writing table over which said strip may be fed and positioned for entry of a record thereon, a strip positioning detent over which the strip passes when fed forwardly to said writing table, said strip being weakened on transverse lines against bending resistance and engaging said detent at said weakened lines 5 to vary the resistance to strip feed, so as to assist in positioning the strip in writing position upon said writing table, and a closure for said compartment coacting with said strip to guide and position it relatively to 10 said detent during strip feed.

2. A portable autographic register including in combination, a casing having a compartment for storing superposed supply strips with blank forms spaced therealong 20 folded into a zigzag supply pad, a writing table overlying said compartment over which said strips may be fed and positioned for entry of a record thereon, said casing having a strip exit slot leading from said 25 compartment near one end of said writing table means for supporting a transfer strip or strips over the writing table between adjacent record strips, a strip positioning detent adjacent said slot and positioned at one 30 end of and in definite relation with said writing table over which the strips pass when fed forwardly to said writing table, guides at both sides of said detent for directing said strips to turn sharply thereabout, one positioned where the strips emerge from said 35 compartment and the other positioned adjacent said writing table, the folds of said strips cooperating with said detent when passing thereover to effect longitudinal 40 alignment of the blank forms and to check the feeding movement of said strips when in writing position upon said writing table.

3. A portable autographic register including in combination, a casing having a compartment for storing a supply strip, a writing table over which said strip may be fed and positioned for entry of a record thereon, said casing having a strip exit slot leading from said compartment near one 45 end of said writing table, a strip positioning detent in the path of said strip and having a definite longitudinal relation therein with reference to said table including a plate extending transversely of the direction of strip 50 feed and having angularly disposed faces forming an apex around which the strip turns in its course from said compartment to said writing table, and guiding means including said slot for restraining the strip 55 into contact with and to turn about said detent during strip feed so as to check the strip in writing position upon said writing table.

4. In a device of the character described, 60 in combination, a casing having a compart-

ment for storing a zigzag supply pack having a plurality of supply strips folded therein and having blank forms spaced therealong, a writing table overlying said compartment over which said strips may be fed in superposed relation and positioned for entry of a record thereon, means for supporting a transfer strip over the writing table between adjacent record strips, a transverse edge formed at the forward part of 70 said writing table providing a strip positioning detent having a definite relation with said writing table and lying in the path of said strips between said compartment and said writing table over which detent said strips pass when fed from said compartment to said writing table, said transverse edge cooperating with a folded line of said strips to effect alignment of the forms thereon when the strips are fed forwardly and to signal to the operator upon advancement of a predetermined strip length, a filling passageway for said compartment at one end of said casing and a closure for said passageway having one edge 80 lying adjacent said transverse edge to form a guide for said strips.

5. A manifolding autographic register adapted to be supported by the operator while inscription is being made and including, in combination, a casing adapted to contain a supply of record strips and having a writing table, said casing having, at its front end a door cooperative with said table to form a slot therebetween for passage 100 of record strips, when the door is closed, so as to position and guide the strip with reference to the later mentioned strip checking edge and a guide strip spaced above said table adjacent its forward end adapted 105 to guide the record strips close to the upper surface of the writing table, the forward end of said table having a depending flange meeting the outer face of said table at an angle to provide a transverse strip 110 checking edge.

6. In a device of the character described, in combination, a casing having a compartment for storing a supply of record strip having blank forms spaced thereon, a writing table overlying said compartment over which the record strip may be fed and positioned for entry of a record thereon, a strip checking detent including a transverse checking edge positioned rearwardly of the writing table and between the latter and said compartment in the path of strip feed so as to engage strip folds to check strip advancement when a blank form is in writing position on the writing table, a movable strip clamping bar positioned relatively forwardly of the writing table so as to clamp the forwardly fed end of the strip and a conical strip aligning pin positioned adjacent said clamping bar so as to engage in a strip 120 125 130

aperture when said bar is in clamping position and when a strip fold is engaged by said checking edge.

7. An autographic register comprising, in combination, a portable box forming a casing for a supply of record strips, the upper wall of said box providing a writing table, the rear upright wall of said box being movable to form a door of the casing, a transversely extending strip checking edge positioned in the strip path between said strip supply and said writing table, the upper edge of said door terminating short of the upper part of the casing when the door is closed so as to provide a guide passageway for the strip at one side of said checking edge, a strip guide closely overlying but spaced from the strip path adjacent to but at the other side of said checking edge, strip aligning posts upstanding from said upper wall forwardly thereof, and manually operable means movably mounted on said box adapted to hold the strips closely adjacent to said posts, being movable to strip releasing position.

8. In a device of the character described, in combination, a casing having a compartment for storing a record strip, a writing table over which said strip may be fed and positioned for entry of a record thereon, a downturned flange at one end of said writing table bent sharply so as to provide a transversely extending edge forming a strip positioning detent correlated with the writing table over which the strip passes when fed forwardly to said writing table, said strip being weakened on transverse lines against bending resistance and engaging said detent at said weakened lines to check strip feed so as to assist in positioning the strip in writing position upon said writing table, and transverse guiding members adjacent to said detent positioned both forwardly and rearwardly thereof with reference to the path of strip feed for guiding said strip to turn sharply about said detent.

9. In a device of the character described, in combination, a casing having a compartment for storing a record strip, a writing table overlying said compartment upon which said strip may be fed and positioned for entry of a record thereon, a downturned flange on said writing table inclined to the plane of the latter so as to form an acute-angled transverse strip positioning detent at the forward part of said writing table and lying in the path of said strip between said compartment and said writing table, over which detent the strip passes when fed forwardly to the writing table, said strip being weakened on transverse lines against bending resistance so as to fold over said detent and to increase resistance to strip feed, thus checking the strip in writing position upon said writing table,

said detent having a definite longitudinal relation with reference to said writing table so as to check the writing areas of the record strip at a definite position upon the writing table, and a filling passage-way for said compartment at the end of said casing having a closure with one edge lying adjacent said detent to form a guide for said strip.

10. In a device of the character described, in combination, a casing having a compartment for storing a plurality of supply strips having blank forms spaced therealong, a writing table overlying said compartment over which said strips may be fed in superposed relation and positioned for entry of a record thereon, means for supporting a transfer strip over the writing table between adjacent record strips, a down-turned, inwardly inclined flange at the rear of the writing table, forming an acute angled transverse edge lying in the path of said strips between said compartment and said writing table and providing a strip positioning detent longitudinally correlated with said table, said strips passing over said detent when fed from said compartment to said writing table, said transverse edge cooperating with weakened lines on said strips to effect alignment of the forms thereon when the strips are fed forwardly so as to check the strips and signal to the operator when writing areas of said strip are in correct writing position on the writing table, a clamping plate for holding the forwardly fed ends of the strips mounted for movement toward and away from strip clamping position, and an aligning pin adjacent to said clamping plate for engagement in apertures in said strips, said pin being spaced forwardly of said strip positioning detent a definite distance so as to enter strip apertures when the detent is in engagement with a weakened line of the strip.

11. An autographic register including, in combination, a casing having a compartment for storing a supply record strip, a writing table over which said strip may be fed and positioned for entry of a record thereon, said casing having a strip exit through which said record strip may pass in its path from said compartment to a position near one end of said writing table, a strip positioning detent in the path of said record strip near said end of said writing table and having angularly disposed faces forming an apex extending transversely of strip feed around which the record strip turns in its path from said compartment to said writing table, strip guiding means for restraining the record strip into contact with and to turn abruptly about said apex during strip feed so that the apex will engage with strip folds to check strip

advancement and to position the strip adjacent said end of the writing table when a strip inscription area is in writing position upon said writing table, and at least 5 one strip aperture engaging strip positioning pin spaced longitudinally of the writing table from said apex and being engageable with strip apertures to retain the strip in writing position at the opposite end of said 10 writing table.

In testimony whereof I affix my signature.

EDWARD KIRBY BOTTLE.
